(57) **CLAIM**

An ornamental design for hat mounted pig tail holders, as shown and described.

DESCRIPTION

FIG. 1 is a perspective view of the hat mounted pig tail holders;

FIG. 2 is a front elevation view of the hat mounted pig tail holders;

FIG. 3 is a side elevation view of one of the hat mounted pig tail holders, the opposite side view being a mirror reflection thereof;

FIG. 4 is a top plan view of the hat mounted pig tail holders; and,

FIG. 5 is a bottom plan view of the hat mounted pig tail holders.

The broken lines of a baseball-style cap, a woman's head, neck and shoulders shown in FIG. 1, as well as the groups of arcs radiating from the claimed design shown in FIGS. 2–5, illustrate environmental matter and form no part of the claimed design. The small areas comprised of a fine cross-hatched pattern interspersed between ribbing, although shown intermittently, are meant to represent texture, and are understood to be distributed uniformly over the surfaces of the claimed design.
